UNITED STATES PATENT OFFICE.

LOUIS V. MALLORY AND ROBB F. BEST, OF KANSAS CITY, MISSOURI.

REMOVABLE CROWN-BRASS-LOCKING DEVICE.

Application filed June 5, 1922. Serial No. 566,180.

To all whom it may concern:

Be it known that LOUIS V. MALLORY and ROBB F. BEST, citizens of the United States of America, residing at Kansas City, in the county of Jackson and State of Missouri, have invented certain new and useful Improvements in Removable Crown-Brass-Locking Devices, of which the following is a specification.

10 Our invention relates to journal boxes and bearings and the primary object thereof is to provide a locking means for holding a removable crown brass in functional position. In actual practice it is quite difficult to provide an efficient means for removably securing the crown brasses in place so they can be detached from the journal box in an expeditious manner as well as being held rigid when they are functioning.

15 Our invention contemplates the provision of means for providing a novel inexpensive easily applied locking means for the crown brass and to this end the invention consists in certain novel parts and combination of parts which will be fully described hereinafter, reference being had to the accompanying drawings, in which—

20 Fig. 1 is an end view of a journal box, the axle and parts of the locking mechanism being shown in section.

25 Fig. 2 is a vertical sectional view through the journal box with the axle removed.

30 Fig. 3 is a perspective view of the upper toggle plate of the locking mechanism for the crown brass.

35 Fig. 4 is a similar view of the lower plate and

40 Fig. 5 is a perspective view of the sleeve nut or head for drawing the toggle plates into locking position.

45 Referring now to the drawings by numerals of reference—

50 1 designates the journal box provided with a crown brass 2 having end flanges 3 and 4 which overlap the shoulders 5 and 6 of the journal box so that the crown brass is held against longitudinal movement. The crown brass, as is usual, consists of a concavo-convex member substantially semi-circular in cross section and one longitudinal edge 7 rests upon a shoulder 8 in the journal box. The opposite edge of the crown brass is supported by a toggle lever mechanism. The toggle lever mechanism is shown as consisting of 55 two elongated plates 9 and 10 (best shown in Figs. 3 and 4). The top edge of the up-

per plate 9 is adapted to contact with the lower edge of the crown brass and the lower edge of the lower plate 10 is rounded at 60 11 to be received in a groove or recess 12 in the journal box (see Fig. 1). The meeting edges of the plates 9 and 10 are provided near their respective ends with half round stepped notches 13 and 14, 15 and 16 respectively, so that when the plates are 65 brought together edge to edge the half round notches 13 and 15 constitute one stepped circular recess and the half round notches 14 and 16 constitute another stepped circular recess, the recesses becoming smaller 70 toward the outer faces thereof. The stepped recesses receive removable heads or sleeve nuts 17 and 18 which are also stepped to conform to the stepped recesses formed by the notches 13, 14, 15 and 16. Each sleeve 75 80 or head is substantially like that shown in Fig. 5 and each is provided with a notch 19 to receive a pin 20 adapted to also engage either of the notches 21 or 22 in the plate 9 so that the removable heads or sleeve nuts 85 17 and 18 will be held against rotation.

85 The heads or sleeve nuts are internally threaded and are engaged by threaded ends on draw bolts 23 and 24. On the outer ends of the draw bolts which project through the bosses 25 on the journal box are nuts 26 held against turning by jam nuts 27 as will be well understood.

90 The parts are carefully machined. The crown brass is first put in place in the usual way so that its flanges 3 and 4 will overlap the shoulders 5 and 6. Then the plates are put in place with the lower edge 11 of the lower plate 10 resting in the recess 12 and the lower edge of the upper plate resting 95 upon the upper edge of the lower plate with the meeting edges of the two plates bowed out slightly from the vertical wall of the journal box. A wrench is then applied to the nuts 26 to draw the draw bolts and thereby snap the toggle plates to aligning positions shown in Fig. 1. It will require considerable tension to draw the toggle plates to this position but when they are in place as shown in Fig. 1 they will hold the crown brass rigid. After the draw bolts are caused 100 to pull the toggle plates in the position shown in Fig. 1, the lock nut is applied. The whole structure is then rigid. When it is desired to remove the crown brass, a 105 wrench may be applied to the polygonal end 28 of each draw bolt 23 or 24 to unscrew the

draw bolt from the removable head, then the head may be released from the recess which it engages and the two toggle plates may be plied outwardly by inserting a tool between them and their meeting edges and the side of the journal box. A slight outward pressure will snap the plates loose so that the crown brass may be removed.

It will be apparent from the foregoing 10 that the crown brass may be readily applied and disassembled from the journal box and that the crown brass will be securely held in place by the toggle levers or plates.

What we claim and desire to secure by 15 Letters Patent is:

1. In combination a journal box having a shoulder, a crown brass having one edge resting on the shoulder, a seat in the journal box, a pair of toggle levers, one of which 20 rests in the seat and the other of which is adapted to engage an edge of the crown brass and means for operating the toggle levers to hold the crown brass rigidly with respect to the journal box.

2. In combination a journal box having a shoulder, a crown brass having one edge resting on the shoulder, a seat in the journal box, a pair of toggle levers, one of which 30 rests in the seat and the other of which is adapted to engage an edge of the crown brass rigidly with respect to the journal box, said means comprising draw bolts passing through the journal box and having heads engaging the levers.

3. In combination a journal box having a shoulder, a crown brass having one edge resting on the shoulder, a seat in the journal box, a pair of toggle levers, one of which 35

rests in the seat and the other of which is adapted to engage an edge of the crown 40 brass rigidly with respect to the journal box, said means comprising draw bolts passing through the journal box and having removable heads engaging the levers.

4. In combination a journal box, a crown 45 brass in the top of the journal box having end flanges overlapping shoulders on the journal box to prevent longitudinal movement of the crown brass, a shoulder portion on the journal box constituting a rest for 50 one edge of the crown brass, the opposite edge of the crown brass being unsupported and toggle levers engaging the journal box and adapted to engage the unsupported edge of the crown brass to hold it rigidly 55 with respect to the journal box.

5. In combination a journal box, a crown brass in the top of the journal box having end flanges overlapping shoulders on the journal box to prevent longitudinal movement of the crown brass, a shoulder portion on the journal box constituting a rest for 60 one edge of the crown brass, the opposite edge of the crown brass being unsupported and toggle levers engaging the journal box 65 and adapted to engage the unsupported edge of the crown brass to hold it rigidly with respect to the journal box, said toggle levers comprising two elongated plates having half round notches, heads in the notches and draw bolts removably engaging the heads. 70

In testimony whereof we affix our signatures.

LOUIS V. MALLORY.
ROBB F. BEST.
